WILLIAM WARWICK STENNING, OF LONDON, ENGLAND, ASSIGNOR TO MINERALS
SEPARATION NORTH AMERICAN CORPORATION, OF NEW YORK, N. Y.

CONCENTRATION OF COAL.

Application filed February 15, 1924, Serial No. 692,955, and in Great Britain February 16, 1923.

This invention consists of improvements in or relating to the concentration of coal, and particularly relates to improvements applicable directly to the means at present in use 5 for washing coal.

In existing coal washing plants a typical and ordinary method is as follows:—The coal as mined is passed over three-inch grizzlies (bar screens), and the material that 10 passes through is sent to the washery to be cleaned by jigs. The first jig through which the material passes is adjusted so that the wash water carries as much as possible of the coal, while the coarse shale is eliminated. 15 The finer portions of the recovered coal still contain a considerable amount of finely divided shale. The recovered product is screened into marketable sizes above half-inch. All material below half-inch is re- 20 elevated by any suitable appliance and the wash water is re-elevated by a centrifugal pump to a second jig adjusted to deal with this size of material. The recovered coal, together with the whole of the wash water, 25 passes to drainage screens, filters, drainage belts, drainage bunkers, or the like: the water from the drainage operation is allowed to settle and is then re-used for washing.

In jigs and equivalent apparatus the 30 principle on which particles of coal are separated from particles of shale is that in water the rate of fall of the coal particles is less than the rate of fall of the shale particles (of comparable size). Concentrators 35 operating on this principle will be referred to herein as gravity concentrators, and in coal washeries the jig is the commonest type.

The existing system above referred to is 40 subject to several important defects. The method is not adapted to the concentration of coal particles of linear dimensions less than $\frac{1}{8}$ of an inch. Fine particles of coal and shale settle very slowly, and the wash water containing these fine particles progressively thickens in re-use, and its specific 45 gravity increases, with the result that the action of the jigs, which depends on the difference between the rate of fall of the coal particles and the shale particles respectively in the liquid, is affected detrimentally. Further, a serious loss of fine coal is incurred. There is often a difficulty in the 50 drainage of the coal which is concentrated,

and on the other hand the settlement of 55 shale, gangue, and other suspended matter from the wash waters is exceedingly troublesome.

In coal washing of the type which involves the use of jigs or like gravity concentrators and/or settling tanks in which aqueous liquor or coal-bearing pulp is pumped by a centrifugal pump from one part of the apparatus to another, the advantages of the present invention may be 60 obtained by introducing air into the centrifugal pump, and adding to the aqueous liquor, before or when it enters the pump, a small proportion (say 0.1% or less) of a 65 frothing agent such as cresol, with or without a small proportion (say 0.1% or less) of a froth-stabilizing agent such as kerosene oil, anthracene oil or creosote oil. The percentages referred to are measured on the weight of the crude or screened 70 coal to be treated.

This invention also includes in coal washery apparatus the combination with a gravity concentrator, such as a jig, and a centrifugal pump arranged to deliver 80 aqueous liquor or coal pulp thereto, of means for introducing air, as into the zone of reduced pressure of the pump, and means for introducing a frothing agent and/or oil or like flotation agent as into the liquor or pulp 85 entering the centrifugal pump.

The invention further includes in a coal washery the combination with a washery water reservoir of an outlet for slurry leading to an agitator and aerator (conveniently 90 a centrifugal pump having an air inlet to its suction zone), means for introducing frothing agent, as to the slurry before its admission to the agitator, and a chamber communicating with the outlet from the 95 agitator in which the pulp may come to a state of comparative rest so that a coal-bearing froth may rise and be removed.

The results of the treatment according to this invention are, firstly, that the mixture 100 of coal, shale, and water is aerated when it is introduced into the jig (the air being very finely subdivided owing to the agitation in presence of the frothing agent), and this aeration diminishes the specific gravity of 105 the pulp (i. e. diminishes the density of the fluid medium as a whole) and so facilitates the jiggling operation, i. e. facilitates the fall

of the comparatively large particles of shale through the pulp. A second and more important result is that the finely divided coal is flocculated, floated and removed with the rest of the coal, and the whole is recovered in the drainage bunkers or other drainage apparatus. In the case where an oil or the like has been used, all the coal has an increased tendency to be separated from water, but in any case, owing to the flocculated condition of the fine coal, produced by the added reagents and the aeration and agitation, the drainage of the coal is facilitated; and the water which drains away carries only finely divided shale in suspension. The settlement of the shale in the settling tanks is also facilitated.

The accompanying drawing is a diagrammatic representation of a typical coal washing plant to which the present invention has been applied.

The coal is delivered on to a grizzly 10 which allows pieces smaller than $3\frac{1}{2}$ " in linear dimensions to drop into the well 11 of an elevator 12. The coal delivered by the elevator is carried by the force of a stream of water, issuing from a pipe 13 into a jig 14. The jig 14 is adjusted to remove shale coarser than one half-inch, which passes to a bin 15. The coarse and fine coal with the fine shale pass to a screen 16. Sizes of coal above one half-inch are graded by the screen and passed to bins diagrammatically shown at 17. Coal and shale below one half-inch pass the screen and are collected with the water from the jig at 18 and passed to a centrifugal pump 19.

The centrifugal pump 19 conducts the material to a second jig 20. This pump 19 is provided with an air inlet 21 on the suction side of the pump and air in quantities suitable for aeration and flotation is introduced, either by the suction or assisted by pressure. At or near the inlet for pulp to the centrifugal pump 19 an inlet 22 is provided for flotation agents, and there is added a frothing agent, such as cresol, at the rate of about 2 lbs. or less per ton of coal, and a froth-stabilizing agent, such as kerosene oil, at the rate of 3 lbs. or less per ton of coal. Where sea-water is used in the washery, the frothing agent may be omitted, or reduced in quantity.

In the second jig 20 the finely divided coal rises to the surface in the form of a froth. There are also some light floccules which are very readily carried upwards in the jig, and the separate coal particles not included in the froth are recovered by the normal operation of the jig. The overflow containing the recovered coal passes to the drainage belt 23 and all the coal which has been recovered in the froth, or in floccules, together with larger discrete particles, is retained on the drainage surface. Thus when the treatment

in the second jig is thoroughly efficacious the water carries away only shale and other gangue slime.

The drained fine coal passes to a storage bin 24 and the water passes to a settling tank 25. The overflow from the settling tank 25 is re-elevated by a centrifugal pump 26 to the first jig 14, and any make-up water which is required may also pass through the pump 26. This pump may be supplied with air through an inlet 27, and, unless the circuit water already contains sufficient, frothing and/or froth-stabilizing reagents may be added at 28. As a result a substantial amount of fine coal is recovered with the coarse coal in the first jiggling operation the remainder of the fine coal being recovered by flotation in the second jiggling operation.

In coal washeries it is a common practice to employ a large conical or V-shaped tank 25 as a reservoir for circuit water. The tank 25 is shown herein as of such a construction. The water which has been used in the various stages of coal washing is ordinarily run into such a V-tank. The water usually carries slurry with it. Commonly the V-tank is arranged with an inlet near the top, an outlet for slurry at the bottom and an overflow launder around the upper periphery, into which comparatively pure water overflows on its way back to the washery for further use. This tank is frequently referred to as the washery water reservoir.

If the water entering the tank 25 contains any fine coal still in suspension, as for example if the treatment in the jig 20 has failed to remove all traces of coal, or if the addition of the air and frothing agents at 21, 22 is omitted, it is desirable that such fine coal shall be removed before the water is returned for re-use in the circuit.

According to this invention therefore the outlet 29 for slurry from the tank 25 may deliver to a centrifugal pump 30 which has an inlet 31 for air and an inlet 32 for a frothing agent such as cresol, with or without a small proportion of froth-stabilizing agent. The aerated and agitated pulp is then led by a pipe 33 into a chamber 34 in which the pulp comes to a state of comparative rest. Here a coal-bearing froth may rise to the surface and be removed. The lower part of the chamber 34 is connected by a conduit 35 to the washery water reservoir 25, so that the washery water, substantially depleted of its coal content, is returned to the reservoir. The chamber 34 in which the froth is formed may be provided at its lower part with an outlet 36 for gangue. Relatively clean water therefore overflows the tank 25 and is returned for reuse.

Hitherto coal particles of linear dimensions exceeding $\frac{1}{8}$ of an inch have been successfully separated, from impurities by well-known coal-washing apparatus, such

as jigs. Finely divided coal particles, particularly those of linear dimensions less than $\frac{1}{16}$ of an inch have been successfully separated from impurities by froth-flotation, and 5 methods have been suggested, for example in British patent to Jones and Minerals Separation Ltd. No. 183,504, for separating the coal particles of intermediate sizes from associated matter. It will be seen that according to the present invention the concentration of coal particles of all dimensions dealt with in coal washing (e. g. from 3 inches downwards) is successively accomplished in one series of operations, and as 10 no special or expensive plant is required in addition to that already commonly in use, the benefits of this invention can be obtained without increased cost, increased labour, or increased power.

20 I claim:

1. The process of separating coal from coarse and fine broken shale-bearing coal which consists in passing the broken shale-bearing coal through a bubble containing liquid in the presence of a reagent facilitating the formation of a froth so that coarse coal is separated from the intermixed coarse shale by differential settling in such liquid of the shale to a level below the coal and fine 25 coal tends to adhere to bubbles and to be lifted thereby out of the shale layer, and separating the coarse and fine coal from the liquid.

2. The process of separating coal from coarse and fine broken shale-bearing coal which consists in passing the broken shale-bearing coal through a liquid containing a flocculating agent tending to flocculate the fine coal so that coarse coal is separated from 30 the intermixed coarse shale by differential settling in such liquid of the shale to a level below the coarse coal and fine coal tends to flocculate into shale-free agglomerates and associate itself in such liquid with the coarse 35 coal, and separating coarse and fine coal substantially together from the liquid carrying the shale.

3. The process of separating coal from coarse and fine broken shale-bearing coal, the coarse coal being too coarse to be floated by bubble action, which consists in passing the broken shale-bearing coal through a liquid containing multitudes of bubbles which lower the density of the liquid and also containing a frothing agent which stabilizes the bubbles so that such coarse coal is gravitationally separated from the intermixed coarse shale by differential settling of the shale in such liquid, and separating such 40 coarse coal from the liquid.

4. The process of separating coal from coarse and fine broken shale-bearing coal which consists in agitating a liquid containing a frothing agent to entrain multitudes of bubbles and passing the broken shale-bear-

ing coal with said bubble-containing liquid through a jig so that the coarse coal is separated from the intermixed coarse shale by differential settling of the shale, and separating the coarse coal from the liquid. 70

5. The process of separating coal from coarse and fine broken shale-bearing coal which consists in agitating water containing a mineral-frothing agent to entrain multitudes of bubbles and passing a pulp of said 75 coal and bubble-containing water through a jig so that the coarse coal is separated from the intermixed coarse shale by differential settling of the shale in the pulp, and separating the purified coal from the top of the 80 pulp partly by the gravity concentration and partly by froth-flotation.

6. The process of separating coal from coarse and fine shale-bearing coal, the coarse coal being too coarse to be floated by bubble 85 action, which consists in passing the broken shale-bearing coal through a liquid so that coarse shale is gravitationally separated from intermixed coarse coal by differential settling of the coarse shale in such liquid, over- 90 flowing liquid carrying such coarse coal and fine solids in suspension, separating such coarse coal from the liquid and fine solids, agitating the separated liquid containing fine 95 solids with a frothing agent to entrain multitudes of bubbles so that the light bubbles tend to offset the weight of suspended solids remaining in the liquid, passing further broken shale-bearing coal through the liquid containing the entrained bubbles to gravita- 100 tionally separate intermixed coarse shale therefrom by differential settling of the shale, and separating further coal from the latter liquid.

7. The process of separating coal from 105 coarse and fine broken shale-bearing coal, the coarse coal being too coarse to be floated by bubble action, which consists in passing the broken shale-bearing coal through a liquid so that such coarse coal is gravitationally 110 separated from intermixed coarse shale by differential settling of the shale in such liquid, separating the coal and liquid carrying unsettled shale from the settled shale, agitating the separated liquid carrying the un- 115 settled shale and the coal with a frothing agent to entrain multitudes of bubbles in such liquid so that the light bubbles tend to offset the weight of suspended solids remaining in the liquid to permit a further quantity of shale to settle therein, and separating 120 from the liquid and further settled shale the coal carried in the liquid.

8. The process of separating coal from coarse and fine broken shale-bearing coal, the coarse coal being too coarse to be floated by bubble action, which consists in passing the broken shale-bearing coal through a liquid so that such coarse coal is gravita- 125 tionally separated from intermixed coarse 130

- 1 shale by differential settling of shale, separating the coal and liquid from the settled shale, agitating the separated liquid carrying the unsettled shale and the coal with a 5 frothing agent to entrain multitudes of bubbles in such liquid so that the light bubbles tend to offset the weight of suspended solids remaining in the liquid to permit a further quantity of shale to settle therein, 10 such agitation also forming a coal-bearing froth, separating the coal-bearing froth from the liquid, and separately separating coarse coal from the liquid.
9. The process which consists in agitating 15 impure coal in water in a series of gravity water concentrators, adding a flocculating agent between two concentrators so that the water in a concentrator normally delivering finer coal also delivers flocculated coal particles, separating the purified coal from its 20 accompanying water, and returning the separated water to the first concentrator.
10. The process which consists in effecting 25 a partial concentration of an impure coal in a jig by separating part of the coal, conveying the remaining coal in a pulp to a second jig, agitating and adding a flocculating agent intermediate the jigs, effecting further concentration in the second jig, 30 draining the accompanying water from concentrated coal, and returning the separated water to the first jig.
11. The process which consists in effecting 35 a partial concentration of an impure coal in a jig by separating part of the coal, conveying the remaining coal in a pulp to a second jig through a centrifugal pump, adding air and a flocculating agent during 40 said conveyance, effecting further concentration in the second jig, draining the accompanying water from the concentrated coal, and returning the separated water to the first jig.
12. The process of separating coal from 45 broken coarse and fine shale-bearing coal,
- the coarse coal being too coarse to be floated by bubble action, which consists in separating coarse shale from such coarse coal in liquid suspension in a jig, conveying to a second jig the solids and liquid separated 50 from coarse shale, agitating and aerating the liquid containing the solids in the second jig in the presence of a flocculating agent to flocculate the particles of fine coal, and separating substantially together such coarse 55 coal and flocculated fine coal from the liquid and other solids.
13. A coal concentrating apparatus comprising a jig, a second jig, means for agitating coal and conveying it from the first jig 60 to the second jig, and means for adding a flocculating agent between the jigs so that the coal is agitated in its presence.
14. A coal concentrating apparatus comprising a jig, a second jig, a centrifugal 65 pump for agitating coal and conveying it from the first jig to the second jig, and means for adding air and a flocculating agent between the jigs so that the coal is agitated with the air and agent by the pump. 70
15. A coal concentrating apparatus comprising a jig, a second jig, means for agitating and conveying coal from the first jig to the second jig, means for adding a flocculating agent between the jigs so that the 75 coal is agitated with the agent, means for separating concentrated coal from the water, and means for returning the water to a jig.
16. A coal concentrating apparatus comprising a jig, a second jig, a centrifugal 80 pump for agitating and conveying coal from the first jig to the second jig, means for adding air and a flocculating agent so that the coal is agitated by the pump with the air and agent, means for separating concentrated coal from the water, and means for returning the water to the first jig. 85

In testimony whereof I affix my signature.

WILLIAM WARWICK STENNING.
